(Cl. D89—1)

To all whom it may concern:

Be it known that we, Benjamin Cooper, Albert F. Hohmann, and Alfons Bach, citizens of the United States, residing at New York city, Teaneck, and Stamford, in the counties of New York, Bergen, and Fairfield, and States of New York, New Jersey, and Connecticut, respectively, have invented a new, original, and ornamental Design for Combination Orange Juicer and Liquefying Unit, of which the following is a specification, reference being had to the accompanying drawing, forming part thereof.

In the drawing:

Fig. 1 is a side elevational view of combination orange juicer and liquefying unit, showing my new design;

Fig. 2 is a front view with the liquefier glass removed;

Fig. 3 is a top plan view with the liquefier glass removed; and

Fig. 4 is a top plan view with the juicer receptacle removed.

We claim:

The ornamental design for a combination orange juicer and liquefying unit, as shown.

BENJAMIN COOPER.

ALBERT F. HOHmann.

ALFONS BACH.
